UNITED STATES PATENT OFFICE

2,603,543

PICNIC TABLE WITH ADJUSTABLE TOP

Rene E. Barbin, Beverly, Mass.

Application May 28, 1949, Serial No. 95,997

2 Claims. (Cl. 311—36)

1

This invention comprises a new and improved picnic or lawn table having novel features of adjustability which render it particularly convenient and desirable for its intended purpose. It is, moreover, of such construction that it may be collapsed into small compass for convenience in transportation and may be produced at very moderate cost.

In its preferred embodiment the table of my invention comprises a shaft or stake passing through a perforated table top and having connecting elements, one hinged to the table top to permit angular adjustment thereof and another being longitudinally adjustable on a shaft to permit height-wise adjustment. The user may thus drive the supporting shaft or stake at any convenient angle determined by the contour or character of the location and angularly adjust the table top to horizontal position. He may also move the table top up and down and clamp it at the desired height.

Going more into detail, the picnic table of my invention in its preferred form may employ as the connecting elements above mentioned a circular plate carried by a tubular head which is slideable upon the shaft, and this plate may be hinged at one edge to the under side of the table top and may have at its other side an adjustable connection to an arm curved about the axis of the hinge. I thus provide connecting elements of simple construction whereby the table top may be held securely at any selected angle to its supporting shaft or stake. Moreover, when the stake is set in vertical position the circular plate will serve to close the perforation in the table top.

These and other features of the invention will be best understood and appreciated from the following description of a preferred embodiment thereof, selected for purposes of illustration and shown in the accompanying drawings in which:

Fig. 1 is a view in elevation, partly in section.

Fig. 2 is a fragmentary view of the table top and connecting elements as seen from beneath, and

Fig. 3 is a view of the table as seen from beneath with a portion of the table top broken away.

The illustrated embodiment of my invention includes in its structure a shaft or stake 10 which may be of wood or metal and sharpened at its lower end so that it may be easily driven into the ground at any selected point. Slidably mounted upon the shaft 10 is a shouldered tubular head 11 having at its upper end a thick

knurled flange 12 and having in one side a set screw 13 by which the head may be clamped in any desired position upon the shaft 10.

Fastened to the upper face of the flange 12 is 5 one of the connecting elements, namely a circular plate 14. This may be secured to the flange 12 by screws or rivets and is provided at one edge with a hinge 15 by which it is connected to the under side of the table top 16. The latter 10 may be circular in outline or any other desired shape. It is preferably constructed of sheet metal and formed with a corrugated flanged rim which not only stiffens the table top as a whole but provides it with a low circumferential retaining wall. The table top 16 is provided with a central perforation 17 which may take the form of an elongated slot providing for the passage of the shaft with clearance through the table top at any convenient angle.

20 A curved and slotted arm 18 is secured by rivets or otherwise to the under side of the table top and this arm extends downwardly in an arc described about the axis of the hinge 15. The circular plate 14 is provided at its free edge with 25 an ear 19 which is curved downwardly and conformed to the arm 18. It is provided with a bolt and wing nut 20 by which the plate 14 and arm 18 may be clamped together in any selected position of angular adjustment.

30 From the foregoing description it will be apparent that when the shaft 10 is driven into the ground at an angle, the wing nut 20 may be loosened and the table top swung about the axis of the hinge 15 into horizontal position regardless of the angle of the shaft. It may then be clamped in horizontal position and adjusted bodily up and down upon the shaft by loosening the set screw 13. Finally, when brought to the 35 most convenient position for its intended use it may be clamped at the desired height by tightening the set screw 13. On the other hand, when it is desired to transport the table from one place to another, the shaft 10 may be slipped out of the head 11 and the circular plate 14

40 moved into substantial contact with the under face of the table top. The two parts thus lie in flat condition and may be conveniently transported while they occupy little space.

Having thus disclosed my invention and 45 described in detail an illustrative embodiment thereof, I claim as new and desire to secure by Letters Patent:

1. A picnic table including in its structure a shaft, a shouldered tubular head movable upon 50 said shaft and having a circular plate fastened

to its upper end, a table top having a perforation substantially larger than the shaft for receiving the shaft in different angular positions, a hinged connection between one edge of the circular plate and the table top, a stationary arm secure to the table top at the other side of the circular plate and being curved on a radius about the axis of the hinged connection, a correspondingly curved ear fastened to the circular plate and arranged to slide in contact with said curved arm, and means for adjustably clamping the ear to the said arm.

2. A picnic table including in its structure a shaft, a tubular head adjustably mounted upon the shaft and having a circular plate secured to its upper end, a flanged table top having a perforation larger than the shaft for receiving the shaft in different angular positions, a hinged connection between the circular plate and the table top, a stationary arm secured to the table top and extending adjacent to one side of the

circular plate and being curved on a radius about the axis of the hinged connection, a connecting member interposed between the circular plate in sliding contact with said curved arm, and means for adjustably clamping the connecting member to said arm.
